UNITED STATES PATENT OFFICE.

BERT LINDSAY, OF ANTIGO, WISCONSIN, ASSIGNOR OF ONE-FOURTH TO LEON LINDSAY, ONE-FOURTH TO FRANK LINDSAY, AND ONE-FOURTH TO WILLIAM LINDSAY, ALL OF ANTIGO, WISCONSIN.

AUTOMATIC LOCK NUT.

Application filed May 5, 1921. Serial No. 466,931.

To all whom it may concern:

Be it known that I, BERT LINDSAY, a citizen of the United States, and resident of Antigo, in the county of Langlade and State 5 of Wisconsin, have invented certain new and useful Improvements in Automatic Lock Nuts; and I do hereby declare that the following is a full, clear, and exact description thereof.

10 My invention refers to nut locks, and has for its object to provide a simple, economical and effective means for locking a nut upon its companion bolt, together with a controlled means for releasing the locking engagement 15 between the nut and bolt.

With the above objects in view, the invention consists in what is herein illustrated, described and particularly defined in the claim.

20 In the drawings,

Figure 1 represents a face view of a bolt and nut embodying the features of my invention.

Figure 2 is a fragmentary sectional view 25 illustrating the nut locking means retracted from its engagement with the bolt, the section being indicated by line 2—2 of Figure 3.

Figure 3 is a longitudinal section view, the section being indicated by line 3—3 of 30 Figure 1, and

Figure 4 is a detail sectional view through the nut illustrating the locking means carried thereby, the section being indicated by line 4—4 of Figure 1.

35 Referring by characters to the drawings, 1 represents a threaded bolt having a series of longitudinal grooves cut in the threads, forming ratchet teeth 2, which ratchet teeth as shown interrupt the threads.

40 A standard nut 3 is provided, the bore of which is formed with a rectangular cavity 4 therein, which cavity is adapted to receive a reciprocative skeleton plunger 5 having a ratchet tooth 5' that is adapted to suc-

45 cessively engage the ratchet teeth 2 when the nut is turned on, and to normally lock the nut in its adjusted position, whereby it is held against twisting, due to vibration or other causes after said nut has been tightened.

50 The rectangular plunger, as best shown in Figure 2, is formed with a central key receiving recess, one upper wall 7 and one of

the side walls 7' being disposed at a right angle to each other. The terminals of these 55 walls are connected by a curved face 7'', which face is concentric to a circular aperture 8 that is formed in the outer face of the nut and communicates with the key recess. This aperture 8 also has a slot extension 8' that is adapted to receive a winged key 9.

Fitted between the bottom of the cavity 4 and the juxtaposed upper face of the plunger is a coil spring 10, which spring normally 60 serves to force the tooth of the plunger into engagement with the grooves of the bolt.

From the foregoing description, it will be seen that when the nut is adjusted to the bolt, the spring controlled plunger will successively drop into the ratchet grooves 2, as said nut is turned in the direction of the arrow. When completely turned up, the plunger tooth will find a locking seat in connection with one of the ratchet grooves, and 70 thus prevent the nut from turning in a reverse direction, whereby it is firmly locked.

Should it be desired to remove the nut for any purpose, the key 9 is inserted through the aperture 8 in the face of the nut to thus enter the key receiving aperture of the plunger, in which entering position the wing of the key will lie approximately parallel 75 to the aperture face 7''. The key is then

swung upwardly whereby its wing portion will engage the face 7 to lift the plunger in opposition to its spring in such a position that the tooth of the plunger is removed 80 from its engagement with the bolt groove, and owing to the fact that the key wing will ride slightly past the center of force exerted upon it, the plunger will be locked in

85 such elevated position until the key is again turned. Hence, the bolt can readily thereby be removed. It is understood that I may 90 vary the structural features within the language of the claim.

I claim:

95 In a threaded bolt having a series of longitudinal ratchet tooth grooves interrupting its threads; the combination of a key having a cylindrical portion and a wing portion; a nut having an aperture of key hole shape and a radial cavity extending 100 from its bore and open only at the bore, a 105 spring controlled tooth plunger mounted in

the cavity for engagement with the ratchet tooth bolt grooves, the plunger being provided with a recess for receiving said key having walls radiating from the key aperture of the nut, one of which is adapted to be engaged by the wing of said key, whereby the plunger is lifted in opposition to its

spring and held in such lifting position by the mere rotation of the shaft of the key.

In testimony that I claim the foregoing ¹⁰ I have hereunto set my hand at Antigo, in the county of Langlade and State of Wisconsin.

BERT LINDSAY.
